UNITED STATES PATENT OFFICE

LUDGER E. LA ERIE, OF SOUTH BEND, INDIANA, ASSIGNOR TO BENDIX BRAKE COMPANY, OF SOUTH BEND, INDIANA, A CORPORATION OF ILLINOIS

BRAKE

Application filed February 25, 1929. Serial No. 342,539.

This invention relates to brakes, and is illustrated as embodied in an internal expanding brake for an automobile. An object of the invention is to provide a simple self-adjusting anchorage for the brake, preferably embodying a novel compression linkage suitable for use in a brake having overlapping shoes. I prefer to use a single anchor post linked to the overlapping shoes, and arranged to serve as a positioning stop engaged by both shoes when the brake is released, the anchor being placed in the angle between the shoes to give it this double function.

The above and other objects and features of the invention, including various novel and desirable details of construction, will be apparent from the following description of one illustrative embodiment shown in the accompanying drawing, in which:

Figure 1 is a vertical section through the brake, just inside the head of the brake drum, and showing the brake shoes in side elevation;

Figure 2 is a partial section through the anchorage, on the line 2—2 of Figure 1;

Figure 3 is a partial section through the anchor post and through the overlapping ends of the shoes, on the line 3—3 of Figure 1; and

Figure 4 is a partial section on the line 4—4 of Figure 1, showing the floating pivot connecting the primary and secondary shoes.

The illustrated brake includes a rotatable drum 10, at the open side of which is a support such as a backing plate 12, and within which is the brake friction means, including for example three shoes 14, 16, and 18. The brake is applied by means such as a double cam 20, acting against the resistance of return springs 22 to apply shoes 14 and 18, shoe 16 being applied by shoe 14 to which it is connected by a floating pivot 24.

The present invention relates to the anchorage of the brake, and while well adapted for use in a brake of the three shoe type such as described above it is not limited to such use and may be embodied in other types of brakes.

In the particular embodiment illustrated, there is a single fixed anchor post 30, carried

by the backing plate and arranged in the angle between shoes 16 and 18, and which is connected to shoes 16 and 18 some distance from their overlapping ends by means such as compression links 32 and 34 pivoted on the anchor post and connected to the shoes by pivots 36 and 38.

Shoe 16 has two parallel spaced stiffening webs, the ends of which embrace and overlap the end of the single stiffening web of shoe 18, and these overlapped portions of the shoes engage anchor 30 when the brake is released, the anchor 30 thus serving also as a positioning stop determining the released position of the anchored ends of shoes 16 and 18.

The shoe 18 is held by the upper return spring 22 against cam 20 and anchor 30, when released, while the released position of the anchored end of shoe 16 is determined by an auxiliary spring 40 urging it to a position determined by anchor 30 and link 32. Thus the links 32 and 34 are freely pivoted at both ends and yet the released positions of shoes 16 and 18 are positively determined.

While one illustrative embodiment has been described in detail, it is not my intention to limit the scope of the invention to that particular embodiment, or otherwise than by the terms of the appended claims.

I claim:

1. A brake comprising, in combination, a pair of shoes one of which has at its end spaced portions embracing and overlapping the end of the other, a fixed anchor in the angle between the overlapping ends of the shoes and arranged to serve as a stop engaged by both shoes when the brake is released, and means connecting said anchor to both shoes.

2. A brake comprising, in combination, a pair of shoes one of which has at its end spaced portions embracing and overlapping the end of the other, a fixed anchor adjacent the overlapping ends of the shoes and means connecting said anchor to both shoes.

3. A brake comprising, in combination, a pair of shoes one of which has at its end spaced portions embracing and overlapping the end of the other, a fixed anchor in the angle between the overlapping ends of the shoes and arranged to serve as a stop engaged

by both shoes when the brake is released, and a compression link connecting each shoe to the anchor.

4. A brake comprising, in combination, a pair of shoes one of which has at its end spaced portions embracing and overlapping the end of the other, a fixed anchor adjacent the overlapping ends of the shoes, and a compression link connecting each shoe to the anchor.

5. A brake comprising, in combination, a pair of shoes having adjacent ends, anchorage means adjacent said ends and serving as a stop engaged by said ends when the brake is released, and means connecting the shoes to the anchor.

6. A brake comprising, in combination, a pair of shoes having adjacent ends, anchorage means adjacent said ends and serving as a stop engaged by said ends when the brake is released, and a compression link connecting each shoe to the anchor.

7. A brake comprising, in combination, a pair of shoes having overlapping ends engaging a fixed stop when the brake is released, and compression anchor links engaging the shoes some distance from the overlapping ends.

8. A brake comprising, in combination, a pair of shoes having overlapping ends engaging a fixed stop when the brake is released, and torque-taking means engaged by the shoes some distance from said ends.

9. A brake comprising, in combination, a pair of shoes having overlapping ends engaging a fixed stop when the brake is released, and pivoted torque-taking means engaged by the shoes some distance from said ends and transmitting the torque to a fixed anchor.

10. A brake having a pair of overlapping shoes linked some distance from their ends to a fixed anchorage adjacent said ends.

11. A brake having a pair of overlapping shoes linked some distance from their ends to a common fixed anchor adjacent said ends.

12. A brake having a pair of overlapping shoes linked some distance from their ends to a common fixed anchor.

13. A brake having a pair of overlapping shoes linked some distance from their ends to a fixed anchorage.

In testimony whereof, I have hereunto signed my name.

LUDGER E. LA BRIE.
